VALVE

Robert F. Falberg, Birmingham, Mich., assignor to General Motors Corporation, Detroit, Mich., a corporation of Delaware

Original application November 7, 1956, Serial No. 620,972. Divided and this application March 3, 1958, Serial No. 718,676

5 Claims. (Cl. 251—73)

This application is a divisional of application Serial No. 620,972, filed in the U.S. Patent Office November 7, 1956, entitled Free Piston Engine Starter.

This invention relates to starting free piston engines, gasifiers, or compressors. The invention relates more particularly to automatic starting of free piston machines using an automatic sequential starting cycle and to the devices used for controlling the timing and positioning of elements of the starting system.

Free piston machines require relatively complex starting mechanisms compared to the simple starting devices used in piston type internal combustion engines wherein the pistons are mechanically connected to each other and to the output shaft. Certain operations such as moving the pistons to their outer positions, holding them in this position while providing a build up of pressure on the pistons, and subsequently releasing the holding means to allow the pressure to move the pistons inward, require accurate timing and positioning devices in order that these steps be performed in proper sequence. Heretofore, electrical solenoids, relays and solenoid operated valves as well as manual controls have been utilized to perform these functions. Electrically reversible motor driven pumps have been used for creating the force necessary to perform steps during the starting procedure. These electrical components generally are expensive, bulky and require considerable space. Furthermore, complex electrical systems require considerable maintenance.

It is therefore an object of this invention to provide a system employing a unidirectional starting pump for positioning the motor and compressor pistons during the starting cycle.

An additional object is to provide a simple mechanically operated device to control the sequential events of the starting cycle of a free piston machine.

These and other objects and advantages of the invention will be readily apparent from the following specification and drawings which illustrate a preferred embodiment of the invention but which are not to be considered as limiting the invention.

The preferred embodiment of the invention comprises a unidirectional air pump that is alternatively connected to create a vacuum in the cushion chambers of the free piston machine and pull the pistons to their outer position, or connected to create a positive pressure in the chambers to push the pistons to their inner position. The alternative actions depend on the position of a control valve that alternatively connects the pump intake or supply to the cushion chambers. This control valve is initially moved between its evacuating and pressurizing positions by the pistons themselves and then by a spring urged piston acting on the valve through a cam device. The control valve is held in its pressurizing position by a latch mechanism until air pressure from air spring piston has returned to its original position. Initial movement of the control valve from its vacuuming position to its pressurizing position is accomplished mechanically by the

2

engine pistons themselves. The latch means that holds the pistons in their outer positions during the starting cycle is also operated and controlled by fluid pressure in the system.

5 Referring to the drawings:

Figure 1 is a diagrammatic sectional view of a dual free piston machine;

Figure 2 illustrates schematically a portion of the starter control system for the free piston machine of Figure 1 in one condition of operation; and

Figure 3 illustrates the starter system in another condition of operation.

Figure 1 of the drawings diagrammatically shows a dual unit free piston machine that could be used as a gasifier for providing a continuous supply of gases under high pressure and temperature to a prime mover such as a gas turbine, although the machine could be adapted for use as a gas compressor or other purposes than as a gasifier for a turbine.

20 The engine includes a case or housing 1, a portion of which defines two motor cylinders 2 in which are reciprocably mounted opposed motor pistons 3. Each motor cylinder 2 has inlet ports 4 and exhaust ports 5 at opposite ends of the cylinder. These ports are opened and 25 closed by the motor pistons 3 which are rigid with large compressor pistons 6 that are mounted for reciprocation in the compressor cylinders 7 also formed as part of the engine case 1. Each compressor cylinder has an inlet port 8 controlled by a valve 9 urged to its closed position by spring 10, and an exhaust port 11 controlled by a valve 12 urged to its closed position by a spring 13. The opposed movable masses of the pistons 3 and 6 of each unit are kept in proper relationship with each other by a separate synchronizing linkage 14 for each unit, which may be of known type. The individual units are designated by A and B in Fig. 1. It is to be understood that a single unit machine may also be utilized in the invention.

25 The two units of the engine are operated on a known 40 supercharged two stroke diesel engine principle. Initial movement of the movable masses 3—6 towards each other causes entrapment of supercharged air and further compression of the air in the motor cylinders 2. At the proper time, fuel is injected by suitable means (not shown) 45 into the compressed air between the motor pistons and is ignited by the heat of compression. The increase in pressure created by the burning fuel acts on the opposed faces of the motor pistons 3 and forces the movable masses 3—6 away from each other.

50 The compressor cylinder 7 is divided by the compressor piston 6 into a compression chamber 16 and a cushion or bounce chamber 17. When the movable masses 3—6 are moved outward, their outward motion is checked by air trapped in the pneumatic cushion chamber 17, which 55 then possesses practically all of the energy developed by the motor cylinder 2 and restores this energy to the movable masses 3—6 during the next inward stroke. The motor cylinder 2 is scavenged by air drawn in through the inlet valves 9 during outward movement of the masses 3—6, compressed in chamber 16 during the inward stroke of the masses 3—6, and delivered through the discharge valves 12 into the case chamber 18. A connecting passage 19 provides for equalizing the pressure in the two case chambers 18. On the next outward stroke of the masses 3—6 the air under pressure in the case chamber 18 enters the motor cylinder 2 through inlet port 4 and travels through the motor cylinder 2 and out exhaust ports 5 into the exhaust collector 63 and then to some power generating device such as a gas turbine.

70 The cushion chambers 17 of each unit are connected together by suitable means 68 to balance the pressures in the opposite chambers. The pressure in the cham-

bers after starting is controlled by a stabilizer **S** which is of known type, such as those shown in U.S. Patent No. 2,355,924. The stabilizer which forms no part of this invention operates only after the starting cycle is completed.

The two units **A** and **B** would normally be connected together by conduit **66** through a normally open isolating valve **I** such as that shown in application U.S. S.N. 584,744 to Warren H. Smith, filed May 14, 1956, now Patent No. 2,839,911. This valve would operate to isolate the chambers after starting when a dephaser **D**, which may be of known type such as those described in U.S. Patent No. 2,473,204, would act to vary the speed on one unit relative to the other until the pistons of one unit are approximately at the inner dead center when the pistons of the other unit are at outer dead center. The isolating valve, stabilizer and dephaser are described in the application and patents referred to and the details are immaterial to this invention and, hence, are not described. The starting control shown in Figs. 2 and 3 is connected to the machine at conduit **26**.

Figs. 2 and 3 show the portion of the control system used to maneuver the opposed masses **3—6** during the starting operation. The controls consist primarily of: (1) a unidirectional air pump; (2) synchronizer linkages **14** and a latch mechanism **20**; and (3) a maneuvering control valve generally indicated at **30**. Briefly, the starting cycle is as follows: (1) the movable masses **3—6** are moved outward by the creation of a vacuum in the cushion chambers **17**; (2) a latching mechanism is then moved into the return path of the linkages **14** connected to the masses **3—6**; (3) a positive pressure is then introduced into the cushion chambers **17** to move the masses **3—6** inward until stopped by the latch mechanism; (4) the pressure in chambers **17** is built up to a predetermined level; and (5) the latch mechanism releases the movable masses **3—6**, allowing the compressed air in the chamber **17** to force the movable masses in towards each other.

The synchronizing and latching mechanisms **14** and **20** include a link **21** secured to a shaft **22** having on either end a latch member **23** which can be rotated into the path of an arm **24** pivotally mounted on a fixed pivot **25**. The arm **24** of each unit has its opposite ends connected by linkage to the opposed compressor pistons **6** of that unit. In the holding position (Fig. 2) of the latch mechanism, the latch **23** is in the path of the arm **24** so that when air pressure is introduced into chambers **17**, pressure acts on the movable mass **3—6** to move the same slowly inward until the arm **24** engages the latch **23**. Pressure in the chamber **17** then rises to a predetermined level, whereupon the controls cause movement of piston **27** of the latch mechanism **20** to rapidly move the linkage **21**. This rotates the shaft **22** and latch **23** to the position shown in Fig. 3, thereby releasing the movable masses **3—6** and allowing the air under pressure in the chamber **17** to move the movable masses **3—6** rapidly inward.

To control the movement of piston **27** which operates the latch **23** and to alternate the connections between a pump **45** and chamber **17**, there is provided a positioning control valve assembly indicated at **30**. This valve assembly consists of a valve body **31** enclosing a spool valve member **32** having four lands **32a**, **32b**, **32c** and **32d**. The valve body **31** is connected to the pump through passages **46** and **47**, to the latch control mechanism by passage **60**, to the engine cushion chambers by passage **51**, and to the atmosphere through passages **54**, **62** and vents **52**. Formed on a portion of the valve member **32** extending through the casing **31** is an enlarged bifurcated section **65** having an inclined cam surface **33** and an adjacent flat surface **33a**. A cam follower **34** having a cam roller **34a** is reciprocably mounted in a housing or chamber **38** attached to valve body **31** for cooperation with the surfaces **33** and **33a**. The por-

tion **65** of the valve member **32** carried outside the casing **31** has a latch member **35** pivotally connected thereto by a pin **35a**. As shown in Fig. 2, this latch **35** is urged to its upper position by a spring **36**. The cam follower **34** is normally urged downward as viewed in the figures by a spring **37** contained within the cam follower chamber **38**. A valve spring **39** continuously acts between the left hand end of the valve casing **31** and land **32a** of the valve member to urge it to its right hand or evacuating position. The left hand end of the valve **32** is connected to a balance arm **40** by a pin **41**. As seen in Fig. 1 the opposite ends of the balance arm **40** are disposed in the path of push rods **42** that have heads **43** formed thereon adapted to engage the opposite ends of the balance arm **40**. These push rods are normally urged outward by springs **44**. The push rods **42** extend into the compression cylinder **7** and are adapted to be engaged and moved by the compressor piston **6** at the close of the outward movement of the pistons during the starting cycle, but are not engaged by the pistons during the normal operating stroke of the pistons when trapped air in the chambers **17** limits outward movement of the pistons **6**.

The piston maneuvering and controlling fluid pressures are produced by a fluid pump schematically indicated at **45**. This pump may be driven by any suitable means such as an electric motor, air motor or other device and has an intake passage **46** and a supply passage **47**. The pump passages **46** and **47** are connected into the control valve body **31**. A passage **51** extends from the valve body **31** to a passage **26** through a chamber **48** in which a check valve **49** is urged by a spring **50** to close the conduit **51** from communication with the passage **26**. Passage **26** is connected to the cushion chambers **17** of the free piston engine. When energized, the pump **45** acts either to create a vacuum in the cushion chamber **17** or to create a pressure in that chamber, depending on the position of the control valve **32**. The valve **32** in Fig. 2 is shown connecting the pump for pressurizing the chamber **17** and in Fig. 3 for evacuating the chamber **17**.

In the vacuumizing or normal position of Fig. 3 the cam follower **34** is in the upper portion of its stroke and the roller **34a** is in contact with surface **33a**, with the spring **39** maintaining the valve **32** in its right hand position. Upon operation of the pump **45** air is withdrawn from chambers **17** through the passage **26**, check valve **49**, passage **51**, between lands **32a** and **32b** of the valve member **32**, through intake passage **46**, and into the pump **45**. The air is then forced out line **47** through the valve body **31** and to the atmosphere through vents **52**. This evacuating of chamber **17** causes the movable masses **3—6** to move towards its outwardmost position until the compressor pistons **6** engage push rods **42** (see Fig. 1). Further movement of the compressor pistons **6** causes enough movement of the push rods **42** and, consequently, balance arm **40** to move the valve **32** slightly to the left as viewed in the figures. This movement of the valve **32** is sufficient to allow the push rod roller **34a** to be moved from a position of rest on surface **33a** to a position on the cam surface **33**. The force of the cam follower spring **37** imparted to the push rod roller **34a** forces the spool valve **32** to move rapidly to the left by imparting a resultant force to the left on the cam **33**. During its movement down cam **33**, the push rod roller **34a** depresses the latch **35** which rotates about its pin **35a**. When the cam roller **34a** reaches the bottom of the cam **33**, the latch spring **36** returns the latch to its normal position as shown in Fig. 2.

Movement of the control valve **32** to the left has connected the pump **45** so that it forces air under pressure into chamber **53** of the latch releasing mechanism and, subsequently, into chamber **17**. This action occurs as follows: Referring to Fig. 2 which shows the valve at its pressurizing position, air is drawn from passage **54** into

the valve body 31, through a bore 55 in the valve member 32, a port 56 between lands 32b and 32c, into pump intake passage 46, through the pump 45 and into passage 47, through the control valve between lands 32a and 32b, and through passage 51. Pressure in passage 51 first acts to close the check valve 49 and at the same time opens a check valve 57 against the spring 58 and passes into line 59, through the valve body 31 between lands 32c and 32d, into the line 60 which leads into chamber 53 of the latch releasing mechanism. The air under pressure in chamber 53 moves piston 27 to the left against spring 64 and through the linkage 28, 29 and 21, rotates the shaft 22 and the latches 23 to the locking position as shown in Fig. 2. Near the end of its movement to the left the piston 27 pushes the check valve 49 off its seat, allowing air under pressure in line 51 to pass to line 26 and into the chamber 17.

As the air pressure in the cushion chamber 17 gradually builds up, the movable masses 3-6 move slowly to their inner position until the arms 24 of the synchronizing linkages 14 engage the latches 23. Pressure then continues to build up in chamber 17 until the pressure acting through passage 61 on the lower surface of the cam follower piston 34 moves the piston 34 against the spring 37. The valve 32 remains stationary during this upward movement of the cam follower 34 because the cam follower roller 34a follows the contour of the latch 35, which is held against the roller 34a by the spring force of return spring 39. When the cam follower roller 34a reaches the top of the latch 35 the latch 35 is depressed slightly against spring 36 allowing the spring 39 to return the valve 32 to the position shown in Fig. 3, the follower roller 34a returning to its normal position also. The rapid movement of valve 32 to the right (Figure 3) connects the chamber 53 of the latch control mechanism and passage 60 to the atmosphere through valve body 31 between passages 32c and 32d and exhaust passage 62. With the drop in pressure in chamber 53 the spring 64 moves the linkage 28, 29, 21, shaft 22 and latches 23 unlocking the synchronizer linkages and allowing the pressure in chambers 17 to start a rapid inward movement of the masses 3-6 for the first firing stroke.

After the compressor piston 6 and motor pistons 3 reach a predetermined inner position fuel is injected into the cylinder 2 and the engine operates under its own power. After the engine starts the pump 45 ceases operation and other controls, not shown, operate to regulate the pressure in cushion chamber 17, and to dephase the two free piston units so that a continuous supply of controlled gases under high pressure and temperature are supplied through the exhaust collector 63 to the gas turbine. These controls as well as the gas turbine have not been shown as they form no part of the invention as any form of free piston machine control could be utilized in a machine using the starting system of the present invention.

The operation of the starting system may be briefly summarized as follows: Initially the latch control mechanism 20 and positioning control valve 30 are positioned as shown in Figure 3. The pump 45 is operated whereby air is withdrawn from cushion chamber 17 through passage 26, check valve 49, line 51, between lands 32a and 32b of valve 32, through passage 46 and the pump into line 47, then through the valve body and out vent ports 52. When the pistons 6 reach the outer part of their stroke they engage push rods 42 causing balance arm 49 to move the valve 32 to a position where the cam follower roller 34a engages inclined cam surface 33 and allowing the force of spring 37, which acts through the cam follower 34, to force the valve 32 to the left against spring 39. Movement of valve 32 to the left causes cam follower 34 to move the latch 35 against the spring 36 and when the valve reaches the end of its stroke, Figure 2, the latch is returned by the spring 36 to its upper position blocking movement of the valve 32 to the right.

With the control valve as shown in Figure 2, pump 45 is now connected to draw air through ports 62 or 54 and passage 46 and will force it under pressure through line 47 into passage 51. Pressure in passage 51 acts to close the check valve 49 and also passes through check valve 57, line 59, through the valve 30, line 60 and into chamber 53 where it acts on piston 27 to move the links 28, 29, and 21 against the force of spring 64 to rotate shaft 22 and latch 23 to a blocking position. When the piston 27 has reached the end of its stroke to the left as viewed in the figure it pushes check valve 49 off its seat allowing pressure in line 51 to pass into line 26 and into the cushion chamber 17. The pressure in chamber 17 then moves the pistons 6 inward until the synchronizer arm 24 contacts the latch 23. The pressure in chamber 17 continues to rise and is transmitted through line 61 to act to move the cam follower 34 upward against the force of spring 37, the cam follower 34a meanwhile following the contour of latch 35. When cam follower 34 reaches the upper portion of its stroke, latch 35 is slightly depressed allowing spring 39 to rapidly move valve 32 to the Fig. 3 position, whereupon pressure in chamber 53 acting to hold the latching mechanism in its locking position escapes through passage 60, between lands 32c and 32d and exhaust passage 62. Spring 64 then moves linkage 28, 29 and 21 to move the latch 23 out of the path of linkage arm 24 and allows air under pressure in chamber 17 to rapidly move the pistons 6 inward toward their first firing stroke. The fuel is then injected into combustion chamber 15 and the movable masses 3-6 forced outward, their outward stroke being limited by air trapped in chamber 17. The continued operation of the free piston machine is then controlled in any known manner as by the stabilizer, dephaser and other controls.

The invention provides an improved control apparatus suitable for use in many applications in the art of free piston machine control and the principles of the invention may easily be utilized in other arts through the use of ordinary skill.

It will be apparent to those skilled in the art that many modifications of the system and components thereof may be made within the scope of the invention which is not to be considered as limited by the detailed description of the embodiment shown.

I claim:

1. A valve actuating mechanism for moving a valve from a first operative position to a second operative position including a valve, a first biasing means for urging said valve to its first position with a predetermined force, a cam surface formed on the valve, a cam follower adapted to engage the cam surface in positions of the valve intermediate the first and second positions, a second biasing means for urging the cam follower into engagement with the cam surface to urge the valve toward its second position with a force greater than that of the first biasing means, a second surface formed on said valve, said cam follower engaging said second surface when the valve is in its first position but inoperative to urge said valve to said second position and means to move said valve from said first position to a position where the cam follower engages the cam surface.

2. A valve actuating mechanism for moving a valve from a first operative position to a second operative position including a valve, a cam surface formed on the valve, a cam follower adapted to engage the cam surface in positions of the valve intermediate the first and second positions, biasing means for urging the cam follower into engagement with the cam surface to urge the valve toward its second position with a predetermined force, means connected to said valve to move the valve from said first position to a position where the cam follower engages the cam surface and thereby urges the valve toward its second position, additional means biasing said valve to said first position with a force less than said predetermined force, means for overcoming said first mentioned

biasing means to move said cam follower away from the valve, and a latch carried by said valve adapted to engage said cam follower when the valve is in its second position to hold the valve in the second position until said cam follower is returned to its position out of engagement with the cam surface whereupon said additional biasing means will move the valve from its second position to its first position.

3. A valve actuating mechanism for moving a valve from a first operative position to a second operative position including a valve, a cam surface formed on the valve, a cam follower adapted to engage the cam surface in positions of the valve intermediate the first and second positions, biasing means for urging the cam follower from an original position of engagement with the valve into engagement with the cam surface to move the valve toward its second position, means to move said valve from said first position to a position where the cam follower engages the cam surfaces, additional means biasing said valve to said first position, first mentioned biasing means being stronger than the second, fluid pressure means for overcoming said first mentioned biasing means to move said cam follower away from the valve, a latch carried by said valve adapted to engage said cam follower when the valve is in its second position to hold the valve in the second position until said cam follower is returned to its original position whereupon said additional biasing means will move the valve from its second position to its first position.

4. A valve operator for moving a valve along an axis between a first and a second position including a valve, a member operatively connected to move the valve, said member having two contact surfaces, follower means adapted to successively engage said surfaces upon movement of said member, said follower means engaging said first surface when the valve is in its first position and engaging the second surface in all positions of the valve during movement from the first to the second position, means biasing said follower into contact with said respective surfaces, said first surface being parallel to the axis of movement of said member and the second surface being at an angle to the axis of movement, means to move the member from a position where the follower means contacts said first surface to a position where the follower

means contacts said second surface to transmit at least a portion of the force of said biasing means to urge the member and valve along its axis to its second position, means to move said follower away from contact with said surfaces, and actuating means connected to said valve for moving it to its first position upon predetermined movement of said follower means away from said second surface.

5. A valve operator for moving a valve along an axis between a first and a second position including a valve, a member operatively connected to move the valve, said member having two contact surfaces, follower means adapted to successively engage said surfaces upon movement of said member, said follower means engaging said first surface when the valve is in its first position and engaging the second surface in all positions of the valve during movement from the first to the second position, means biasing said follower into contact with said respective surfaces, said first surface being parallel to the axis of movement of said member and the second surface being at an angle to the axis of movement, means to move the member from a position where the follower means contacts said first surface to a position where the follower means contacts said second surface to transmit at least a portion of the force of said biasing means to urge the member along its axis and valve to its second position, means to move said follower away from contact with said surfaces, actuating means connected to said valve for moving it to its first position upon predetermined movement of said follower means away from said second surface, and holding means carried by said member adapted to contact said follower means for maintaining said valve in its second position, said predetermined movement of said follower away from said second surface acting to render said holding means ineffective to maintain the valve in its second position and thereby allow said actuating means to move said valve to its first position.
